No. 769,210.

PATENTED SEPT. 6, 1904.

B. J. DOBBINS.

FILLING REPLENISHING MECHANISM FOR LOOMS.

APPLICATION FILED JUNE 8, 1904.

NO MODEL.

Fig. 1.

UNITED STATES PATENT OFFICE.

BELVIA J. DOBBINS, OF NINETYSIX, SOUTH CAROLINA, ASSIGNOR TO DRAPER COMPANY, OF HOPEDALE, MASSACHUSETTS, A CORPORATION OF MAINE.

FILLING-REPLENISHING MECHANISM FOR LOOMS.

SPECIFICATION forming part of Letters Patent No. 769,210, dated September 6, 1904.

Application filed June 8, 1904. Serial No. 211,593. (No model.)

To all whom it may concern:

Be it known that I, BELVIA J. DOBBINS, a citizen of the United States, and a resident of Ninety-six, county of Greenwood, State of 5 South Carolina, have invented an Improvement in Filling-Replenishing Mechanism for Looms, of which the following description, in connection with the accompanying drawings, is a specification, like characters on the drawings representing like parts.

This invention relates more particularly to filling-replenishing mechanism of looms of the Northrop type, such as forms the subject-matter of United States Patent No. 529,940; 15 and it has for its object the production of a simple, durable, and effective guide-support and buffer to co-operate with a filling-carrier or bobbin as it is transferred from the filling-feeder to the shuttle.

20 Figure 1 is a side elevation and partial transverse section of a part of a filling-replenishing mechanism of the type referred to with one embodiment of my invention applied thereto. Fig. 2 is an enlarged cross-sectional 25 detail on the line 2 2, Fig. 1, the buffer being shown in elevation; and Fig. 3 is an inner face view, also enlarged, of the stand of the filling-feeder, showing the controlling-spring for the buffer.

30 The lay A³, shuttle S, breast-beam A⁴⁰, having secured to it a stand A⁷, on which is mounted the filling-feeder, (only one of the disks a¹ thereof being shown,) the transerrer f', the means to actuate it to transfer singly 35 the filling-carriers or bobbins b from the feeder to the shuttle, and the means for intermittently rotating the feeder may be all substantially as in United States Patent No. 664,790. As in said patent, an abutment h' 40 on the stand A⁷ serves to direct or guide one side of the head of a filling-carrier during transfer, the abutment forming a fixed side of a discharge-throat leading from the feeder to the shuttle when the lay is in its forward 45 position on front center.

Referring to Fig. 2, I have shown the inner face of the stand A⁷ as provided with a lateral hub 1 below the circular flange a⁵, Fig. 1, near

its lower end and opposite the abutment h', the hub and thickened portion 2 of the stand 50 forming an elongated rigid bearing for a stud 3, parallel to the axis of the feeder. On its outer end the stud is provided with a broad, flat, or plate-like extension 4, substantially at right angles thereto toward the abutment, 55 said extension constituting the movable guide-support or buffer. The inner end of the stud has coiled around it a stout spring 5, one end thereof being upturned at 6 and hooked around a lug a⁷ on the stand A⁷, said lug preferably 60 having a notch 25 to receive the wire, while the other end of the spring is hooked at 7 around a pin 8 on the stud. The spring is so wound as to normally maintain the buffer 4 in the position shown, said abutment extending below the flange a⁵ toward the abutment h' and projecting part way into the path of a filling-carrier when transferred.

At time of transfer the filling-carrier presses against the buffer, which yields and swings 70 downward against the stress of the spring 5, and it acts upon the adjacent side of the head of the filling-carrier, guiding and supporting the same as it is moved down through the discharge-throat. When the transerrer f' 75 rises after a transfer, the spring 5 causes the buffer to return to normal position in readiness for the next transferring operation.

The buffer and its stud are strong and durable and cheap to construct, and it is applied 80 and held in place, as well as controlled, by the spring without any bolts, screws, or other fastening devices, it being manifest from an inspection of Fig. 2 that the spring performs the double function of controller and retaining device for the buffer.

Having fully described my invention, what I claim as new, and desire to secure by Letters Patent, is—

1. An intermittently-movable feeder to hold 90 a plurality of filling-carriers, a stand on which it is mounted, an elongated bearing-hub on and integral with the stand at one side of the path of movement of a filling-carrier when transferred, a transerrer, a stud mounted to 95 rock in the bearing-hub and having a rigidly-

connected buffer to yieldingly support and guide a filling-carrier when transferred, the inner end of the stud projecting beyond the hub, and a spring directly connected at one end with the stud and fixedly connected at its other end with the stand, the spring between its ends being coiled around the stud projecting beyond the hub, to control the angular movement of the stud and retain it in place in the bearing-hub.

2. Filling - replenishing mechanism for looms, including an intermittently-rotatable feeder to hold a series of circularly-arranged filling-carriers, a stand on which it is mounted, a transerrer, an abutment extended into the path of the filling-carrier next to be transferred, a stud with which the buffer is rigidly connected, a pin on the opposite end of the stud, a bearing-hub on the stand and in which the stud is mounted to rock, the inner end of the stud projecting beyond the end of the hub, a coiled spring surrounding the projecting end of the stud, and connected at one end with said pin on the stud, and a lug on the stand near the bearing-hub, the opposite end of the spring being hooked around the lug and fixedly held thereby, the spring acting to

control angular movement of the buffer and also to retain the stud in place in the bearing-hub and prevent its longitudinal movement. 30

3. An intermittently-movable feeder to hold a plurality of filling-carriers, a stand in which it is mounted, a fixed abutment on the stand to form one side of a discharge-throat through which the filling-carriers pass, an elongated bearing-hub on the stand opposite the abutment, a lug on the stand near and parallel to the hub, a stud mounted to rock in said hub and projecting at both ends beyond it, a spring surrounding one end of the stud adjacent the hub and secured at one of its ends directly to the stud, the other end of the spring being detachably secured to the lug and fixedly held thereby, and a buffer rigidly connected with the opposite end of the stud forming a yielding side for the discharge-throat opposite the fixed abutment. 35 40 45

In testimony whereof I have signed my name to this specification in the presence of two subscribing witnesses.

BELVIA J. DOBBINS.
